FLOTATION VEST

Edgar G. Baker, Carbondale, Pa., assignor to Gentex Corporation, New York, N.Y., a corporation of Delaware

Filed May 22, 1963, Ser. No. 75,007

Term of patent 14 years

(Cl. D71—1)

FIGURE 1 is a front elevational view of a floatation vest showing my new design.

FIGURE 2 is a rear elevational view thereof.

FIGURE 3 is a side elevational view thereof, the opposite side, not shown, being substantially the same.

FIGURE 4 is a bottom plan view thereof.

The dominant features of the design reside in the portions shown in full lines, with portions broken away in FIGURES 1 and 2 for convenience of illustration only.

I claim:

The ornamental design for a floatation vest, substantially as shown and described.
